MEASURING AND FILLING MACHINE

Carl G. Meyers, Chicago, Ill., assignor to The Allbright-Nell Company, Chicago, Ill., a corporation of Illinois

Application December 26, 1942, Serial No. 470,202

7 Claims. (Cl. 222—250)

The present invention relates generally to machines for filling containers with measured charges or amounts of liquid material, such as, congealable lard, vegetable oil shortening and the like. More particularly the invention relates to that type of combined measuring and filling machine which is designed for use with, and to form a part of, an automatic container handling apparatus, and comprises as the main parts or elements thereof—(1) a pair of laterally spaced depending nozzles over the container supporting part of the handling apparatus; (2) a cylinder having one end thereof connected by a duct to one of the nozzles and its other end connected by a second duct to the other nozzle; (3) a passage to which the material to be measured is supplied under pressure; (4) a two-position valve mechanism in associated relation with the ducts and the passage and adapted when in one position to close the nozzle end of the first mentioned duct and effect communication between the passage and the cylinder end of the first mentioned duct and also to open the second duct, and further adapted when in its other position to close the nozzle end of the second duct and effect communication between the passage and the cylinder end of the second duct and to open said first mentioned duct; (5) a floating piston mounted in the cylinder to slide back and forth between the ends thereof and adapted when the valve mechanism is in its said one position to be displaced or shifted by the material entering the one end of the cylinder via the cylinder end of said first mentioned duct and to force the material in the other end of the cylinder through the second duct to and through its nozzle, and further adapted when the valve is in its said other position to be oppositely or reversely shifted by the material entering said other end of the cylinder via the inlet end of the second duct and to cause the material between it and said one end of the cylinder to flow through said first mentioned duct to and through its nozzle; and (6) mechanism for automatically shifting the valve mechanism at the end of each stroke of the floating piston.

The primary object of the invention is to provide a measuring and filling machine which is an improvement upon, and has certain advantages over, that which is disclosed in, and forms the subject matter of, United States Letters Patent No. 1,464,676, granted on August 14, 1923, to B. S. Harrington, and in addition is simpler in design and more efficient and positive in operation.

Another object of the invention is to provide

a measuring and filling machine of the type under consideration which includes an improved form of valve mechanism and also novel and simple mechanism for actuating the valve mechanism at the end of each stroke of the floating piston in the cylinder.

A further object of the invention is to provide a measuring and filling machine which is generally of new and improved construction, effectively and efficiently performs its intended function, and is capable of being produced at a comparatively low cost.

Other objects of the invention and the various advantages and characteristics of the present measuring and filling machine will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a front elevation of a measuring and filling machine embodying the invention;

Figure 2 is a side view of the machine;

Figure 3 is a vertical section taken on the line 3—3 of Figure 1 and illustrating in detail the construction and design of the cylinder and the two-position valve mechanism;

Figure 4 is a horizontal section taken on the line 4—4 of Figure 2; and

Figure 5 is a section of the D-valve forming a part of the mechanism for automatically shifting the valve mechanism at the end of each stroke of the floating piston.

The machine which is shown in the drawings constitutes the preferred form or embodiment of the invention. It is designed for use with any suitable automatic container handling apparatus, such, for example, as that illustrated herein. Such apparatus comprises a horizontally elongated table type frame 1 having at the top thereof a longitudinally extending horizontal endless belt (not shown). The upper reach of the belt is suitably supported on the frame 1 and serves to advance in a controlled manner a series of containers 8. The present machine serves as a medium for filling the containers with measured charges or amounts of liquid material, such, for example, as congealable shortening. It is associated with the frame 1 and comprises a pair of laterally spaced, depending nozzle 9 and 10 over

the upper reach of the endless conveyor of the container handling apparatus, a cylinder 11 and a unitary two-position valve mechanism 12. The nozzles 9 and 10 are adapted, as hereinafter described, alternately to discharge the material in measured quantities into the containers therebeneath. The container handling apparatus is adapted to feed the containers in such manner that there is an empty container under each nozzle in connection with discharge of the material therethrough. For a disclosure of a container handling apparatus with which the improved measuring and filling machine may be employed reference may be had to United States patent application Serial No. 471,860, filed January 9, 1943.

The nozzles 9 and 10 are carried at the ends of a horizontally extending member 13 which is positioned above and behind the endless belt of the container handling apparatus. The nozzle carrying member 13 is supported by way of a vertically extending member 14 which is suitably mounted on the frame 7. The upper end of the member 14 is connected to the central portion of the horizontally extending member 13 and the lower end of said member 14 projects beneath the endless conveyor of the container handling apparatus and has a flat horizontal bottom face 15. A duct 16 is formed in the members 14 and 13 and this duct leads from the face 15 to the nozzle 9. A second duct 17 is formed in said members 14 and 13 and this duct leads from the flat face 15 at the lower end of the member 14 to the nozzle 10. A vertically extending passage 18 is formed in the member 14. The upper end of this passage is connected by a pipe 19 to receive the liquid material under pressure from any suitable source. The lower end of the passage 18 leads to and through the flat face 15 at the lower end of the member 14 and is disposed between the lower ends of the ducts 16 and 17.

The cylinder 11 is supported on the frame 7 beneath the vertically extending member 14. It is disposed in a horizontal position and comprises a substantially cylindrical side wall 20 and a pair of fixed circular heads 21 and 22. The head 21 is bolted or otherwise fixedly secured to the right hand end of the cylindrical side wall 20, as viewed in Figures 3 and 4, and the head 22 is suitably attached to the left hand end of the cylinder side wall 20 and serves as a closure therefor. In addition to the side wall and fixed heads the cylinder 11 comprises a false head 23 and this is slidably mounted in the end of the cylinder to which the head 21 is applied. By sliding the false head 23 to and from the head 21 the volume of the space between the false head and the head 22 may be varied and the amounts of the charges of material thus regulated. Sliding movement of the false head 23 to and from the head 21 is effected by means of a screw 24 which extends through a threaded hole 25 in the central portion of the head 21. The inner end of the screw is suitably connected to the outer end of the false head 23 so that it is held against axial displacement relatively to the false head while at the same time it is free to rotate with respect to said false head. The outer end of the screw is disposed exteriorly of the head 21 and is provided with a polygonal head 26 whereby the screw may be gripped by a wrench or similar turning tool and turned in either direction in connection with adjustment of the false head 23. When the screw 24 is turned in one direction the false head 23 is shifted away from the fixed head 21 and hence reduces or

lessens the size of the space between the false head and the fixed head 22. Reverse rotation of the screw 24 causes the false head to move toward the fixed head 21 and results in an increase in the size or volume of said space. The upper portion of the side wall 20 of the cylinder 11 is provided with a flat horizontal face 27 and embodies a pair of ports 28 and 29. The port 28 is so arranged that one end thereof leads to and through the face 27 and its other end communicates with the interior of the cylinder at a point slightly inwards of the fixed head 21 (see Figure 3). The other port is so arranged that one end thereof leads to and through the face 27 and its other end communicates with the interior of the cylinder at a point directly adjacent the fixed head 22. The false head 23 is provided in the upper portion thereof with an angular notch 30 and this serves to maintain at all times communication of the port 28 with the cylinder interior, regardless of the position of the false head. Mounted in the side wall 20 of the cylinder 11 is a floating piston 31. This piston is adapted, as hereinafter described, to slide back and forth in the cylinder between the fixed head 22 and the false head 23. When the floating piston slides to the left, as viewed in Figure 3, the liquid material between it and the fixed head 22 is caused to flow through the port 29 and the duct 17 to and through the nozzle 10. Reverse sliding movement on the part of the piston results in the liquid material between it and the false head 23 being forced through the port 28 and the duct 16 to and through the nozzle 9.

The valve mechanism 12 is interposed between the flat face 15 at the lower end of the member 14 and the flat face 27 on the upper portion of the side wall 20 of the cylinder 11. It serves as an automatic controlling medium whereby the charges of liquid material under pressure are caused alternately to flow through the nozzles 9 and 10. As its main or principal parts the mechanism 12 comprises a housing 32 and a spool type valve 33. The housing has a flat upper face in engagement with the flat face 15 at the lower end of the member 14 and a flat lower face in engagement with the flat face 27 on the upper portion of the cylinder side wall 20. In addition, the housing has a horizontal bore 34 in parallel relation with the cylinder 11, three laterally spaced upper ports 35, 36 and 37 and two laterally spaced lower ports 38 and 39. The upper ports lead from, and communicate with, the upper portion of the bore 34 and the lower ports are in communication with, and lead from, the lower portion of the bore. The port 35 registers with the lower end of the duct 16, the port 36 registers and communicates with the lower end of the passage 18, and the port 37 is in registry with the lower end of the duct 17. As shown in Figure 3, the port 36 is disposed midway between the ports 35 and 37. The lower port 38 registers with the upper end of the port 28 in the upper portion of the cylinder wall 20 and is located at a point substantially midway between the upper ports 35 and 36. The lower port 39 registers and communicates with the upper end of the cylinder port 29 and is so positioned that it is disposed midway between the upper ports 36 and 37. The spool type valve 33 of the valve mechanism 12 is slidably mounted in the bore 34 and has in the central portion thereof a pair of annular, laterally spaced grooves 40 and 41. The ends of the valve project to the outside of the housing 32 and are surrounded by stuffing boxes

42. The valve 33 is shiftable back and forth between two positions. When the valve is shifted to the right as viewed and shown in Figure 3 the groove 40 registers with the ports 35 and 38 and establishes communication therebetween, the groove 41 registers with the ports 36 and 39 and establishes communication therebetween, and the portion of the valve outwards of the groove 41 closes the port 37. When the valve is in its right hand position the liquid material under pressure flows through the passage 18, the port 36, the groove 41, the port 39 and the port 29 and thence into the left hand end of the cylinder, that is, the space between the fixed head 22 and the floating piston 31. By reason of the fact that the material is under pressure the portion of the material entering such space forces the floating piston 31 to slide towards the false head 23. As the floating piston moves towards the false head 23 the material between the piston and the false head is caused to flow through the port 28, the port 38, the groove 40, the port 35 and the duct 16 to and through the nozzle 9. When the valve 33 is shifted to the left the portion thereof that is outwards of the groove 40 closes the port 35, the groove 40 establishes communication between the ports 36 and 38, and the groove 41 establishes communication between the ports 37 and 39. While the valve 33 is shifted to the left the liquid material flows through the passage 18, the port 36, the groove 40, and the ports 38 and 28 into the right hand end of the cylinder, that is, the space between the false head 23 and the floating piston 31. As the material enters such space it forces the floating piston 31 towards the fixed head 22. As the piston slides or travels to the left in response to inflow of the material between it and the false head the material in the left hand end of the cylinder is forced through the ports 29 and 39, the groove 41, the port 37 and the duct 17, and thence to and through the nozzle 10. During each stroke of the piston a measured quantity of the liquid material is forced through one of the nozzles. During shift of the piston to the right a measured quantity of the material is discharged from the nozzle 9 and during reverse shift of the piston, that is, shift to the left, a measured quantity of the material is discharged from the nozzle 10. The charges from the two nozzles are precisely equal. By adjusting the false head 23 toward the fixed head 21 the amount of each charge will be increased. Adjustment of the false head away from the fixed head 21 results in a reduction in the amount or volume of each charge. The spool type valve 33 of the unitary valve mechanism 12 is shifted automatically at the end of each stroke of the floating piston 31 and hence there is a continuous intermittent discharge of the charges of the material from each nozzle.

In addition to the various parts heretofore described the measuring and filling machine comprises means for automatically shifting the spool type valve of the valve mechanism at the end of each stroke of the floating piston in the cylinder 11. This means comprises a pair of axially aligned push rods 43 and 44, a tie rod 45 between the two push rods, a lever 46, a D-valve 47, and a cylinder-piston device 48. The push rod 43 is slidably mounted in a sleeve 49 at the right hand end of the cylinder 11. The inner end of the sleeve extends through, and is fixedly secured within, a bore 50 in the false head 23. The bore 50 is positioned at one side of the center of the false head 23, as shown in Figure 75

4. The outer end of the sleeve 49 extends loosely through a hole 51 in the fixed head 21 of the cylinder 11 and carries a stuffing box 52 for the outer end of the push rod 43. When the false head 23 is adjusted longitudinally of the cylinder the outer end of the sleeve 49 slides relatively to the fixed head 21. The inner end of the push rod 43 projects a small distance inwards of the inner face of the false head 23 with the result that the floating piston 31 abuts against it as it reaches the end of right hand sliding movement and shifts the push rod 43 to the right. The push rod 44 extends longitudinally of the cylinder 11 and is slidably mounted in a sleeve 53 which is fixedly mounted in a bore 54 in the head 22 and is axially aligned with the sleeve 49 for the push rod 43. The outer end of the sleeve 53 is provided with a stuffing box 55 for the outer end of the push rod 44. The inner end of the push rod 44 projects a small distance inwards of the fixed head 22 of the cylinder 11 and hence when the floating piston reaches the end of its stroke in connection with left hand sliding movement it abuts against the push rod 44 and shifts the latter to the left, as viewed in Figure 4. The tie rod 45 is located exteriorly of the cylinder 11 and is positioned in parallel relation with the cylinder side wall 20. It serves to connect the two push rods for conjoint sliding movement and is mounted for axial sliding movement in a pair of apertured lugs 56 on the ends of the cylinder side wall 20. The right hand end of the tie rod is connected to the outer end of the push rod 43 by way of an arm 57. One end of this arm has a socket 58 in which the outer end of the push rod 43 fits. A key type pin 59 serves fixedly or rigidly to secure the outer end of the push rod 43 within the socket with the result that the push rod and arm are rigidly connected together. The other end of the arm 57 has a horizontal bore 60 and surrounds a sleeve 61. The latter is mounted on the right hand end of the tie rod 45 and is connected thereto by a screw thread connection 62. The central portion of the sleeve 61 extends through, and is rotatably mounted within, the bore 60 in said other end of the arm 57. The inner end of the sleeve is provided with an enlargement 63 which abuts against the inner end of the hole defining portion of the arm 57. The outer end of the sleeve is provided with a head 64 having a kerf therein whereby the sleeve may be turned relatively to the tie rod 45. The arm 57 is so arranged that it is caused to move laterally in connection with axial adjustment of the sleeve 61 relatively to the tie rod. When the sleeve is turned in one direction relatively to the tie rod the sleeve, the arm 57 and the push rod 43 move inwards. Reverse rotation of the sleeve results in outward movement or adjustment of the arm 57 and the push rod 43. In order to effect conjoint adjustment of the push rod 43 and the false head 23 a gear 65 and a pinion 66 are provided. The gear is mounted on, and fixedly secured to, the outer end of the screw 24 for adjusting the false head 23. The pinion 66 is fixed to the outer end of the sleeve 61, meshes with the gear 65, and is disposed between the head 64 and the outer end of the bore defining portion of the arm 57. The thread of the screw 24 is a right hand thread and the thread of the screw thread connection 64 is a left hand thread. The two threads are so designed, so far as pitch is concerned, and the gear 65 and the pinion 66 are so proportioned that

when the screw 24 is adjusted in order to slide the false head 23 to and from the fixed head 21 the push rod 43 is adjusted correspondingly. In other words, when the screw 24 is turned so as to shift the false head 23 away from the fixed head 21 the sleeve 61 is so axially displaced that the push rod 43 is caused to follow the false head and maintain its normal position relatively thereto. When the screw 24 is turned so as to shift the false head 23 toward the fixed head 21 in order to increase the size of the measured charges of liquid material the sleeve 61 is so axially displaced with respect to the tie rod that the push rod 43 is caused to follow the false head 23. The gear 65, the pinion 66, the sleeve 61 and the arm 57 constitute simple means for causing the push rod 43 to move conjointly with the false head 23 in connection with adjustment of the latter. The left hand end of the tie rod 45 is connected to the outer end of the push rod 44 by way of an arm 67. One end of the arm 67 is fixedly secured to the left hand end of the tie rod 45 and the other end of the arm has a socket in which the outer end of the push rod 44 is fixedly secured. By reason of the fact that the push rods 43 and 44 are connected together by the tie rod 45 they are caused conjointly to move to the right when the floating piston 31 reaches the end of right hand sliding movement and they are also caused conjointly to shift to the left when the piston approaches the end of its stroke in connection with sliding to the left.

The lever 46 extends vertically and is disposed outwards of the central portion of the tie rod 45. It serves as a medium for controlling the D-valve 47 in response to shift of the tie rod 45. The upper end of the lever 46 is pivotally supported by way of a pivot stud 68 and this, as shown in Figure 2, is secured to, and projects laterally from, the central portion of the side wall 20 of the cylinder 11. The central portion of the lever 46 is operatively connected to the central portion of the tie rod 45 by way of a pin 69. One end of this pin is fixedly connected to a collar 70 on the central portion of the tie rod 45 and the other end of the pin fits within a vertically extending slot 71 in the central portion of the lever 46. When the tie rod 45 is shifted to the right the lever 46 is caused to swing to the right. Reverse shift on the part of the tie rod results in the lever 46 swinging to the left.

The D-valve 47 constitutes a medium for controlling the cylinder-piston device 48. It is mounted on a bracket 12 on the right hand end of the cylinder side wall 20 and comprises a horizontally elongated housing 73 and a slide valve 74 in the housing. The housing has a chamber 75 for the slide valve 74 and embodies a port 76 in the upper portion thereof and three laterally spaced ports 77, 78 and 79 in its bottom portion. The port 76 leads to the chamber 75 and is connected to a source of air under pressure by way of a vertically extending pipe 80. The port 78 is disposed between the ports 77 and 79 and is in the nature of an exhaust port in that it leads to the atmosphere surrounding the D-valve 47. The port 78 communicates with the left hand side of the chamber 75, as viewed in Figure 5, and the port 79 communicates with the right hand end of the chamber 75. The slide valve 74 is mounted on a horizontally extending slide rod 81 and is adapted to slide or move back and forth in the chamber 75 in response to sliding movement of

the slide rod. One end of the slide rod projects through the housing 73 of the D-valve 47 and is connected by a link 82 to the lower end of the lever 46. The bottom portion of the slide valve 74 engages slidably the bottom wall of the housing 73 of the D-valve 47 and has a downwardly facing cavity 83. When the lever 46 is swung to the right, as viewed in Figure 2, the slide valve 74 is caused to slide to the right, as viewed in Figure 5. When the slide valve 74 is slid to the right the port 77 is uncovered and receives air under pressure from the port 76 via the chamber 75 and the port 79 is covered by the slide valve and is in communication with the exhaust port 78 by way of the cavity 83 in the slide valve. When the slide valve 74 is slid to the left hand end of the chamber 75 in connection with left hand shift of the tie rod 45 the port 79 is exposed and receives air under pressure from the port 76 via the chamber 75, and the port 77 is covered by the slide valve and communicates with the exhaust port 78 by way of the cavity 83.

The cylinder and piston device 48 operates to shift the spool type valve 33 of the valve mechanism 12 under control of the D-valve 47. It is located above the cylinder 11 and in alignment with the right hand end of the housing 32 of the valve mechanism 12, and comprises a horizontal cylinder 84 and a piston 85. The cylinder is supported in axial alignment with the spool type valve 33 of the mechanism 12 by way of a bracket 86. It consists of a cylindrical side wall 87 and a pair of fixed heads 88 at the ends of the side wall. A port 89 communicates with the left hand end of the cylinder interior and this port is connected to the port 79 of the D-valve 47 by way of a pipe 90. A port 91 communicates with the right hand end of the interior of the cylinder 84 and this port is connected to the port 77 of the housing 73 of the D-valve by way of a pipe 92. The piston 85 of the device 48 is mounted to slide back and forth between the ends of the cylinder 84 and has the left hand end thereof connected to the right hand end of the spool type valve 33 of the valve mechanism 12 by way of a horizontally extending rod 93. This rod extends through a stuffing box 94 in the head 88 at the left hand end of the cylinder side wall 87. When the slide valve 74 of the D-valve is shifted to the right air under pressure flows into the right hand end of the cylinder 84 via the port 77, the pipe 92 and the port 91 and causes the piston 85 to slide to the left hand end of the cylinder 84. Such sliding movement on the part of the piston 85 serves to shift the spool type valve 33 to the left. When the slide valve 74 of the D-valve is shifted to the right, as shown in Figure 5, the left hand end of the cylinder 84 of the cylinder-piston device 48 is vented by way of the port 89, the pipe 90, the port 79, the cavity 83 and the exhaust port 78. When the slide valve 74 of the D-valve is shifted to the left as the result of the floating piston 31 being shifted against the push rod 44 air under pressure is admitted into the left hand end of the cylinder 84 by way of the chamber 75 in the D-valve housing 73, the port 79, the pipe 90 and the port 89. When the sliding valve 74 is shifted to the left the right hand end of the cylinder 84 is vented by way of the port 91, the pipe 92, the port 77, the cavity 83 and the exhaust port 78.

The operation of the measuring and filling machine is as follows:

When the spool type valve 33 is shifted to the right the liquid material under pressure flows

through the passage 18, the port 36, the groove 41, and the ports 39 and 29 into the left hand end of the cylinder 11. As the material enters the left hand end of the cylinder it forces the floating piston 31 to slide to the right. Such sliding on the part of the floating piston results in the material between it and the false head 23 being forced through the ports 28 and 38, the groove 40, the port 35, and the duct 16 to the nozzle 9 as hereinbefore described. When the floating piston 31 reaches the false head 23 it engages the inner end of the push rod 43 and slides the push rod to the right. This results in the tie rod 45 being shifted to the right and causes the tie rod to swing the lever 46 to the right. Such swinging on the part of the lever causes the slide valve 74 of the D-valve 47 to slide to the right, as viewed in Figure 5. As soon as the slide valve is shifted to the right air under pressure flows through the port 77 from the chamber 75, and thence passes through the pipe 92 to the port 91 and into the right hand end of the cylinder 84 of the cylinder-piston device 48. As soon as air under pressure enters the right hand end of the cylinder 84 it slides the piston 85 to the left and causes the spool type valve 33 of the mechanism 12 to slide to the left. As soon as the spool type valve 33 is slid to the left it closes the port 35 and establishes communication between the ports 36 and 38, and also establishes communication between the ports 37 and 39. When the ports 36 and 38 are in communication with one another the liquid material under pressure flows into the right hand end of the cylinder 11 via the port 28 and causes the floating piston 31 to slide to the left, that is, towards the fixed head 22. During travel of the floating piston 31 to the left the material between it and the fixed head 22 flows through the ports 29 and 39, the groove 41, the port 37 and the duct 17 to and through the nozzle 10. As soon as the floating piston 31 approaches the fixed head 22 it comes in contact with the inner end of the push rod 44 and causes such push rod, together with the tie rod 45 and the push rod 43, to slide to the left. Such sliding movement results in the lever 46 swinging to the left and causing the slide valve 74 of the D-valve 47 to slide to the left hand end of the chamber 75 in the housing 13. When the slide valve 74 is shifted to the left hand end of the chamber 75 air under pressure flows from the chamber 75 through the port 79, the pipe 90, and the port 89 into left hand end of the cylinder 84. As the air flows into the left hand end of the cylinder 84 it forces the piston 85 to the right and this in turn causes the spool type valve 33 of the valve mechanism 12 to slide to the right. Thereafter the same cycle of controlled movements takes place.

The herein described measuring and filling machine is positive in operation. It effectively and efficiently fulfills its intended purpose and is characterized by simplicity of design.

Whereas the machine has been described as being primarily adapted for use in filling containers with measured charges of liquid lard or vegetable oil shortening it may be used in connection with other liquids or semi-liquids. It is also to be understood that the invention is not to be restricted to the details set forth since these may be modified within the scope of the appended claims without departing from the spirit and scope of the invention.

Having thus described the invention what I claim as new and desire to secure by Letters Patent is:

1. A machine adapted to fill containers with measured charges of liquid material and comprising a cylinder having ports at the ends thereof, a floating piston mounted in the cylinder to slide back and forth between the ends, passage forming means connected to receive the material under pressure, a unitary valve mechanism disposed in associated relation with the cylinder and consisting of a housing between the passage and said cylinder and a spool type valve mounted in the housing to slide back and forth between two positions, adapted when in one position to establish communication between the passage and one of the ports and open the other port and when in its other position to establish communication between the passage and said other port and open said one port, and provided at one end thereof with a longitudinally extending rod, and means for automatically shifting the spool type valve of the valve mechanism at the end of each stroke of the floating piston, embodying a fluid pressure actuated piston and cylinder device having the piston thereof mounted on said rod.
2. A machine adapted to fill containers with measured charges of liquid material and comprising a cylinder having ports at the ends thereof, a floating piston mounted in the cylinder to slide back and forth between its ends, passage forming means connected to receive the material under pressure, a two-position valve mechanism between the passage and said cylinder and adapted when in one position to establish communication between the passage and one of the ports and open the other port and when in its other position to establish communication between the passage and said other port and open said one port, and means for automatically operating the valve mechanism at the end of each stroke of the floating piston, embodying a pair of piston actuated push rods extending through the cylinder ends, respectively, into the interior of the cylinder and a tie rod disposed exteriorly of the cylinder, having the ends thereof rigidly connected to the outer ends of the push rods, and serving to connect said push rods together for conjoint sliding movement in both directions.
3. A machine adapted to fill containers with measured charges of liquid material and comprising a cylinder having ports at the ends thereof, a floating piston mounted in the cylinder to slide back and forth between its ends, passage forming means connected to receive the material under pressure, a two-position valve mechanism between the passage and said cylinder and adapted when in one position to establish communication between the passage and one of the ports and open the other port and when in its other position to establish communication between the passage and said other port and open said one port, and means for automatically operating the valve mechanism at the end of each stroke of the floating piston, embodying a pair of piston actuated push rods extending through the cylinder ends, respectively, into the interior of the cylinder, a tie rod disposed exteriorly of the cylinder, having the ends thereof connected to the outer ends of the push rods, and serving to connect said push rods together for conjoint sliding movement in both directions, and a lever having one end thereof mounted on a fixed pivot

and its central portion operatively connected to the tie rod.

4. A machine adapted to fill containers with measured charges of liquid material and comprising a cylinder having ports at the ends thereof, a floating piston mounted in the cylinder to slide back and forth between its ends, passage forming means connected to receive the material under pressure, a two-position valve mechanism between the passage and said cylinder and adapted when in one position to establish communication between the passage and one of the ports and open the other port and when in its other position to establish communication between the passage and said other port and open said one port, and means for automatically operating the valve mechanism at the end of each stroke of the floating piston, embodying a pair of piston actuated push rods extending through the cylinder ends, respectively, into the interior of the cylinder, a slidably mounted tie rod disposed exteriorly and longitudinally of the cylinder, having the ends thereof rigidly connected to the outer ends of the push rods, and serving to connect said push rods together for conjoint sliding movement in both directions, and a lever adjacent the central portion of the tie rod and having one end thereof pivotally supported on a pivot on the cylinder and its central portion operatively connected to said central portion of the tie rod.

5. A machine adapted to fill containers with measured charges of liquid material and comprising a cylinder provided with fixed heads at its ends and embodying a slidably mounted false head inwards of one of the fixed heads and a pair of ports leading, respectively, to the ends of the space in the cylinder between the other fixed head and the false head, a floating piston mounted in the cylinder to slide back and forth between the other fixed head and the false head, passage forming means connected to receive the material under pressure, a two-position valve mechanism between the passage and the cylinder adapted when in one position to establish communication between the passage in one of the ports and open the other port and when in its other position to establish communication between the passage and said other port and open said one port, and means for automatically operating the valve mechanism at the end of each stroke of the floating piston embodying a push rod extending through said other fixed head of the cylinder, a second push rod extending through said one fixed head and the false head, a slidably mounted tie rod disposed exteriorly and longitudinally of the cylinder and having one end thereof fixedly connected to the outer end of the first mentioned push rod, and an arm having one end thereof fixedly connected to the outer end of said second push rod and its other end extending around the other end of the tie rod and connected thereto so that it is adjustable longitudinally of said tie rod.

6. A machine adapted to fill containers with measured charges of liquid material and comprising a cylinder provided with fixed heads at its ends, having a slidably mounted false head inwards of one of the fixed heads, and an adjusting screw therefor extending through said one head, and also embodying a pair of ports leading respectively to the ends of the space in the cylinder between the other fixed head and

the false head, a floating piston mounted in the cylinder to slide back and forth between the other fixed head and the false head, passage forming means connected to receive the material under pressure, a two-position valve mechanism between the passage and the cylinder adapted when in one position to establish communication between the passage and one of the ports and open the other port and when in its other position to establish communication between the passage and said other port and open said one port, means for automatically operating the valve mechanism at the end of each stroke of the floating piston embodying a push rod extending through said other fixed head of the cylinder, a second push rod extending through said one fixed head and the false head, a slidably mounted tie rod disposed exteriorly and longitudinally of the cylinder and having one end thereof fixedly connected to the outer end of the first mentioned push rod, and an arm connected to the outer end of said second push rod and mounted on the other end of the tie rod so that it is longitudinally adjustable relatively thereto, and means operative in response to adjustment of the false head by the adjusting screw automatically to effect corresponding adjustment of the arm relatively to the tie rod.

7. A machine adapted to fill containers with measured charges of liquid material and comprising a cylinder provided with fixed heads at its ends, having a slidably mounted false head inwards of one of the fixed heads, and an adjusting screw therefor extending through said one head, and also embodying a pair of ports leading respectively to the ends of the space in the cylinder between the other fixed head and the false head, a floating piston mounted in the cylinder to slide back and forth between the other fixed head and the false head, passage forming means connected to receive the material under pressure, a two-position valve mechanism between the passage and the cylinder adapted when in one position to establish communication between the passage and one of the ports and open the other port and when in its other position to establish communication between the passage and said other port and open said one port, means for automatically operating the valve mechanism at the end of each stroke of the floating piston embodying a push rod extending through said other fixed head of the cylinder, a second push rod extending through said one fixed head and the false head, a slidably mounted tie rod disposed exteriorly and longitudinally of the cylinder and having one end thereof fixedly connected to the outer end of the first mentioned push rod, a sleeve mounted on the other end of the tie rod and connected thereto by a screw thread so that it is adjustable longitudinally of the tie rod, and an arm having one end thereof connected to the outer end of said second push rod and its other end mounted on the sleeve so that it is adjustable therewith while at the same time permitting the sleeve to rotate relatively thereto, and means for effecting conjoint and corresponding adjustment of the false head and said arm consisting of a gear fixed to the outer end of the adjusting screw and a pinion in mesh with the gear and fixed to said sleeve.

CARL G. MEYERS.
